UNITED STATES PATENT OFFICE

HERMAN BANY, OF YEADON, PENNSYLVANIA, AND GORDON R. McDONALD, OF SCHENECTADY, NEW YORK, ASSIGNORS TO GENERAL ELECTRIC COMPANY, A CORPORATION OF NEW YORK.

SYNCHRONIZING APPARATUS

Application filed November 30, 1928. Serial No. 322,783.

Our invention relates to improvements in synchronizing apparatus and has for an object to provide improved synchronizing apparatus for automatically controlling the operation of connecting two alternating current circuits whereby to minimize the possibility of effecting a connection at the wrong instant.

In order to produce the minimum of disturbance, two alternating current circuits should be connected when their electromotive forces are substantially alike in phase and in frequency. To this end, it is desirable that the closing operation of the connecting means should be started when the frequency difference is small enough and sufficiently ahead of phase coincidence to allow for the time necessary to make the connection. In view of the possibility of a sudden change in the frequency difference between the electromotive forces of the circuits, it is desirable not to start the closing operation until the frequency difference has reached some satisfactory semblance to uniformity. Otherwise, a subsequent sudden change in the frequency difference may result in a disastrous closing. Moreover, it is desirable to take into account the possibility of the failure of parts of the apparatus so as to eliminate the possibility of a bad connection because of such failure. In accordance with our invention, we provide synchronizing apparatus which insures a practical check not only on the condition of the apparatus but also on the uniformity of the frequency difference.

Our invention will be better understood from the following description when considered in connection with the accompanying drawing and its scope will be pointed out in the appended claims.

In the accompanying drawing, Fig. 1 illustrates diagrammatically an embodiment of our invention and Fig. 2 is a vector diagram explanatory of the operation of the embodiment of our invention shown in Fig. 1.

For the purpose of illustration, we have shown in Fig. 1 an embodiment of our invention as applied to a three phase alternating current electric system including an alternating current circuit such as a bus 3 to 50 which may be connected, by any suitable circuit controlling or switching means 4, another alternating current circuit 5 herein shown as including a generator 6. The switching means 4 may be of the latched 55 closed type, and, as shown, includes a closing coil 7 whose circuit is arranged to be energized from a control bus 8 through the contacts 9 of a control relay 10 which is illustrated as instantaneous closing and time delay opening to allow for the time necessary to insure the latching of the switching means. The purpose of the control relay 10 is to relieve the more delicate contacts of the electroresponsive apparatus, hereinafter described and embodying our invention, from the heavy duty involved in directly controlling the circuit of the closing coil 7. Included in the circuit of the control relay 10 for opening the circuit thereof upon closure 60 of the switching means 4 is an auxiliary switch 11 associated with the switching means and arranged to be closed when the switching means is open and vice versa.

For controlling the control relay 10 and 75 through this relay the switching means 4 so as to start the closing operation thereof in time to effect closure when the electromotive forces of the circuits 3 and 5 are substantially alike in phase and frequency and only when 80 the apparatus is functioning satisfactorily and the frequency difference is reasonably uniform, we provide in accordance with our invention electroresponsive means controlled in accordance with the phase difference and 85 the difference between the frequencies of the electromotive forces of the circuits 3 and 5 such that the closing operation of the switching means 4 is started at a predetermined 90 phase difference when the frequency differ-

ence is less than a predetermined value and has been substantially uniform for a satisfactory period and the apparatus is in condition to function as intended. The electro-
responsive means shown in the illustrated em-
bodiment of our invention include a plurality
of relays 12, 13, 14 and 15 which are connected
to be energized from the circuits 3 and 5 and
arranged so that their respective movable
members 16, 17, 18 and 19 must simultaneously
be in predetermined positions in order to
start the closing operation of the connecting
means.

The relays 12 and 13 are disclosed in United States Letters Patent 1,680,708 and 1,680,754, dated August 14, 1928. These relays are of the induction disk type, their respective disks 16 and 17 being controlled by opposing shaded pole motor elements 120, 121 and 130, 131 respectively. In order that the movement of the disks may be dependent upon the phase difference between the electromotive forces of the circuits 3 and 5, the motor elements 120 and 130 are arranged to be energized in accordance with the sum of these electromotive forces and the opposing motor elements 121, 131 in accordance with the difference between the electromotive forces through suitable means including potential transformers 20 and 21. When the difference between the torques exerted by the motor elements 120 and 121 exceeds a predetermined value, the disk 16 is actuated to move its contact controlling member 22 substantially instantaneously through its predetermined position to close the cooperating contacts 23 at a predetermined phase difference. In order that the movable member or disk 17 of the relay 13 may be responsive to the frequency difference between the electromotive forces of the circuits 3 and 5 it is retarded by suitable means such as a drag magnet 24 so that the contact controlling member 25 is able to move to its predetermined position and bridge contacts 26 within a predetermined range of phase difference when the frequency difference is less than a predetermined value for a time sufficient to permit the necessary movement.

The relay 14, as shown, is substantially similar to the relay 13 except that, in accordance with our invention, the opposing motor elements 140, 141 are arranged to move the contact controlling member 27 to bridge the cooperating contacts 28 in a shorter time for a given frequency difference and over a predetermined range of phase difference overlapping that of the relay 13. For this purpose the retardation of the disk 18 by suitable means such as a drag magnet 29 may be less than the retardation of the disk 17 and the shaded poles of the motor elements 140, 141 may be suitably adjusted to provide a different phase difference range.

In accordance with our invention, the relay 15 is of a type responsive to the phase dif-

ference between the electromotive forces of the circuits 3 and 5 and is arranged to tend to actuate its movable member 19 to its predetermined position within a predetermined range of phase difference overlapping a portion of the phase difference range common to the relays 13 and 14. For this purpose, the relay 15 may be of the pivoted armature type and, as shown, includes a fixed magnetic member 30, an energizing winding 31 and a pivoted armature 19 which is arranged to bridge contacts 32 through a contact controlling member 33. The energizing winding 31 is connected to be energized in accordance with a function of the electromotive forces of the circuits 3 and 5. As shown, this function is the vector difference of the electromotive forces obtained by a suitable connection of the winding 31 to the potential transformers 20, 21.

The contacts 23, 26, 28 and 32 of the relays 12, 13, 14 and 15 respectively constitute a plurality of connections in a control circuit arranged to be energized from the control bus 8 and including conductors 34, 35, 36, 37, 38, 39, 40 and 41 such that when all the connections are made, the closing operation of the switching means is started through an auxiliary relay 42 which has its winding in this control circuit and which is arranged to control the circuit of the control relay 10. As shown the conductors 36, 37, 38, 39 and 40 are arranged when the contacts 23, 26, 28 and 32 are closed to short-circuit a current limiting means such as a resistance 43 in series relation with the auxiliary relay 42 to effect the operation thereof. In this manner it is possible to reduce the duty on the contacts of the synchronizing relays 12, 13, 14 and 15 and at the same time to have the relay 42 in effect initially magnetized not sufficiently to permit of its being picked up but great enough to expedite action of the relay at the desired instant. When the switching means 4 is closed, the circuits of both the auxiliary relay 42 and the control relay 10 become deenergized through the opening of the auxiliary switch 11.

The operation of our invention will be apparent from a consideration of the vector diagram shown in Fig. 2 in which OE is taken as a stationary vector representing the electromotive force of the bus 3 in a position considered as the in-phase condition. The other radial lines may be assumed to represent the electromotive force of the circuit 5 in various positions relative to the electromotive force of the bus. The relay 13 is arranged to close its contacts 26 within a range of phase difference represented by the angle 13'E13'' when the frequency difference is less than a predetermined value. Similarly, the relay 14 is arranged to close its contacts 28 within a range of phase difference represented by the angle 14'E14'' when the fre-

quency difference is less than a predetermined value. The phase difference ranges for the relays 13 and 14 overlap and the relay 14 is retarded to a lesser extent than the relay 13 so that it can operate to close its contacts 28 in a shorter time than the relay 13 for a given frequency difference. The relay 15 is arranged to tend to close its contacts at the phase difference indicated by the vector 0-15' and within a range of phase difference measured clockwise from the vector 0-15' to the vector 0-15'' which may be prior to phase coincidence. This relay therefore, tends to have its contacts closed over a range of phase difference represented by the angle 14'-15'' which overlaps a portion of the range of phase difference common to the relays 13 and 14. Within the range of phase difference 14'-15'' common to the relays 12, 13 and 15, the relay 12 is arranged to effect a momentary closure of its contacts 23 at some predetermined phase difference indicated for example by the vector 0-12'. In the discussion herewith, it is assumed that the vector representing the electromotive force of the circuit 5 is rotating clockwise, but the apparatus embodying our invention functions in a similar manner whether the frequency of the circuit 5 is less or greater than that of the circuit 3.

When the frequency difference between the electromotive forces of the circuits 3 and 5 is such that the relays 13 and 14 can close their contacts prior to the phase difference 0-12' and the relay 15 has its contacts closed, then the control circuit for the auxiliary relay 42 is energized sufficiently to effect the pick-up of the control relay 10 and thereby the closing of the switching means 4. Although the relay 12 can in its return movement close its contacts 23 at a position represented by the vector 0-12'', it is ineffective to accomplish anything at this time since the contacts of the relays 13 and 14 are open. It will be apparent from Fig. 2 that if the frequency difference at the phase difference 0-13' is small enough to permit the closing operation of the relay 13 and that at some intermediate point prior to the phase difference 0-12' the frequency difference should suddenly increase, the control circuit would not be closed even though relay 13 had closed its contacts before the phase difference 0-12' since the relay 14 would not have time to close its contacts ahead of this phase difference position. It will be apparent that if for any reason the contacts of one of the relays 12, 13, 14 and 15 should close and stick, the remaining relays will prevent an improper closing of the switching means 4 since closing can take place only within a relatively limited range of phase difference when the frequency difference is less than a predetermined value.

While we have shown and described our

invention in considerable detail, we do not desire to be limited to the exact arrangements shown, but seek to cover in the appended claims all those modifications that fall within the true spirit and scope of our invention.

What we claim as new and desire to secure by Letters Patent of the United States, is:

1. In combination, two alternating current circuits, means for connecting the circuits and means for controlling the closing operation of the connecting means including a plurality of relays connected to be energized from the circuits and arranged so that their movable members must simultaneously be in predetermined positions to start the closing operation of the connecting means, means for retarding the movement of the movable members of two of said relays, means for moving the movable elements of said two relays to their respective predetermined positions in times dependent on the difference between the frequencies of the electromotive forces of said circuits and within predetermined overlapping ranges of phase difference between the electromotive forces, means tending to move the movable member of another of said relays to its predetermined position within a predetermined range of phase difference overlapping a portion of the phase difference common to the movable members of the two relays, and means for actuating the movable member of a fourth one of said relays through its predetermined position at a predetermined phase difference within the range thereof common to the movable members of the first three mentioned relays.

2. In combination, two alternating current circuits, switching means for connecting the circuits, means including a control circuit having a plurality of connections arranged when all are closed to start the closing operation of the switching means, and means for controlling said connections including a plurality of movable members arranged to be controlled in accordance with the phase difference between the electromotive forces of the circuits, means for retarding the movement of one of said members, means for actuating said member to close its respective connection within a predetermined range of phase difference when the frequency difference is less than a predetermined value, means for actuating a second of said members to close its respective connection in a shorter time than said first member and within a predetermined range of phase difference overlapping said first mentioned range when the frequency difference is less than said predetermined value, means tending to move a third of said members to close its connection within a predetermined range of phase difference overlapping a portion of the phase difference.

range common to the first and second movable members and means for actuating a fourth of said members to effect a momentary closure of its connection at a predetermined phase difference within the range thereof common to the first, second and third movable members.

3. In combination, two alternating current circuits, a switch for connecting the

10 circuits and means arranged when simultaneously in predetermined positions to start the closing operation of the switch including two retarded movable members, means for actuating said members in accordance

15 with the sum of and difference between the electromotive forces of the circuits to move the members to their respective predetermined positions in different times and within different predetermined overlapping

20 ranges of phase difference when the frequency difference is less than a predetermined value, a third movable member, means for actuating said third member in accordance with the difference between the elec-

25 tromotive forces to tend to move said third member to its predetermined position within a range of phase difference ending prior to phase coincidence and overlapping a portion of the phase difference range common

30 to the two retarded members, a fourth movable member and means for actuating said fourth member in accordance with the sum of and the difference between the electromotive forces to move said fourth member

35 through its predetermined position substantially instantaneously at a predetermined phase difference within the range thereof common to the first three mentioned members.

4. In combination, two alternating current circuits, a switch for connecting the circuits and means arranged when simultaneously in predetermined positions to start the closing operation of the switch includ-

5 ing two movable members, means for actuating said two members in accordance with the sum of and difference between the elec-

10 trromotive forces of the circuits to move said members to their respective predetermined positions in different times and within different predetermined overlapping ranges of

15 phase difference when the frequency difference is less than a predetermined value, a third movable member, means for actuating said third member in accordance with a function of the electromotive forces to tend

20 to move the member to its predetermined position within a range of phase difference ending prior to phase coincidence and over-

25 lapping a portion of the phase difference range common to said two members, a fourth movable member and means for actuating said fourth member in accordance with the sum of and the difference between the elec-

35 trromotive forces to move the member

through its predetermined position substantially instantaneously at a predetermined phase difference within the range thereof common to the first three mentioned members.

In witness whereof, we have hereunto set our hands this 26th day of November, 1928, and this 14th day of November, 1928, respectively.

HERMAN BANY.
